METHOD OF PREPARING GOODYEAR WELT
INSOLES

Abraham A. Katz, Cambridge, Mass.

Application January 29, 1952, Serial No. 268,800

8 Claims. (Cl. 12—146)

1

This invention pertains to the manufacture of footwear of the Goodyear welt type, and more especially to a method of preparing insoles for use in such footwear.

Foot comfort demands longitudinal flexibility in the shoe bottom, and shoe manufacturers have long sought for constructions or procedures whereby a high degree of flexibility might be attained. However, when the shoe bottom comprises two or more superimposed sole elements, for example, an insole and outer sole, it is very difficult to obtain an ideal degree of flexibility. The most flexible shoe (aside from true moccasins) has been the turn shoe, which has no insole, the outer sole being lasted directly to the upper. While turn shoes, especially for women's wear, have in the past constituted a substantial percentage of the total number of shoes manufactured, the difficulties incident to the making of such shoes, and in particular the necessity for highly skilled hand labor, has discouraged the making of such shoes in recent years, so that the turn shoe process has been relegated largely to the manufacture of slippers or similar soft and generally shapeless articles of footwear.

Next to the turn shoe in flexibility is the Goodyear welt shoe, wherein the outer sole is connected to the insole by a flexible welt strip, which allows a substantial relative motion of the insole and outer sole, thus favoring flexibility. However, the Goodyear welt insole must have a sewing rib to receive the inseam or welt-attaching stitches. In the earlier days of the Goodyear welt process, the insole was usually made of leather and was channeled to provide a lip or lips, which could be turned up to form the sewing rib, but this method required the use of insole stock of substantial thickness and concomitant stiffness. Later, in the effort to obtain a thinner and more flexible insole (and incidentally a cheaper insole), it was proposed to secure a separate rib-forming element to a flat insole blank, so that it was no longer necessary to channel the insole material. A method of providing a flat insole blank with a sewing rib is disclosed, for example, in the patents to Poole, 1,137,282, April 27, 1915, and 1,244,891, October 30, 1917. By following this procedure, it should be possible, in theory at least, to apply a sewing rib to an insole blank of any degree of thinness, but since the machine operation of uniting the rib to the flat blank (for example, as described in the above patents to Poole) involves a progressive feeding or advance of the work, it is necessary that the insole blank have a certain

2

degree of stiffness to prevent it from puckering or buckling as it is advanced. Thus there is a minimum thickness of blank stock necessary to the practical manufacture of insoles according to this prior method, and consequently the maximum obtainable flexibility may be less than that which would be desirable in any given case. However, except for these practical limitations, the insole blank might, for example, be of paper thickness (if possessing a substantial degree of toughness), since in a completed Goodyear welt shoe, the insole has little structural utility.

The present invention has for its principal object the provision of a method of preparing Goodyear welt insoles whereby it becomes possible to use insole material which is substantially devoid of inherent stiffness, and which may be as thin as desired. For example, the selected insole material may be of cloth, plastic sheeting, sheepskin or other flexible sheet material, usually much cheaper than the leather commonly employed as insole stock. Other and further objects and advantages of the invention will be pointed out in the following more detailed description, and by reference to the accompanying drawings, wherein:

Fig. 1 is a plan view of an insole blank according to the present invention;

Fig. 2 is a longitudinal section on the line 2—2 of Fig. 1;

Fig. 3 is a plan view of a reinforce member employed in the practice of the present invention;

Fig. 4 is a longitudinal section on the line 4—4 of Fig. 3;

Fig. 5 is a plan view showing the insole blank and reinforce member assembled in accordance with the present invention in preparation for the attachment of the sewing rib;

Fig. 6 is a longitudinal section on the line 6—6 of Fig. 5;

Fig. 7 is a fragmentary diagrammatic vertical section illustrating the step of applying the rib-forming material to the insole blank;

Fig. 8 is a plan view of the assembled blank and reinforce member, with the ribbing attached to the exposed surface of the blank;

Fig. 9 is a longitudinal section on the line 9—9 of Fig. 8;

Fig. 10 is a plan view of the blank with its attached ribbing after the removal of the reinforce member;

Fig. 11 is a section on the line 11—11 of Fig. 10; and

Fig. 12 is a transverse section on the line 12—12 of Fig. 11.

Referring to the drawings, the numeral 1 designates an insole blank having the size and contour of the insole which is to be made, and which may be made of any desired material and of any degree of thinness, providing, however, that the selected material possesses sufficient toughness to prevent it from tearing during the ribbing-applying operation and during lasting. Among the materials which may be employed for the purpose, but without limitation, may be mentioned woven cloth, sheepskin such as is customarily employed for the lining of shoes, sheeted synthetic resin, or materials made from bats of unspun fiber impregnated with or integrated by means of some plastic substance such as latex.

The numeral 2 designates the reinforce member employed in the practice of the present invention. This reinforce member is of the same size and contour as the insole blank 1, but is made of a material which is inherently stiff and capable of resisting bending in response to stresses tending to wrinkle or buckle it. For example, the reinforce member 2 may be made of commercial fiberboard, such material, of two iron's thickness, having been found to be sufficiently stiff for the purpose.

Having provided the reinforce member 2 and the blank 1, the blank and reinforce member are assembled in registering relation, and are then temporarily united so as to hold them in this assembled relation during the application of the sewing rib. For example, as here illustrated, the parts 1 and 2 are temporarily bound together by strips 3 of adhesive tape, for example, material of the type known as Scotch tape, the strips being folded about the edges of the parts 1 and 2, and arranged at a sufficient number of points to hold the parts 1 and 2 in properly registered relation. Such a means of holding the parts together is very cheap, both as respects the material used and the operation of applying it, but other temporary securing means may be employed, for example, staples, or spots of adhesive interposed between the contacting faces of the members 1 and 2. For the latter purpose, a thermo-plastic adhesive may be employed, which by the application of heat loses its adhesiveness, so that, at the completion of the rib-forming operation, the parts 1 and 2 may readily be separated by the application of heat.

Having assembled the parts 1 and 2 as just described, the sewing rib is then secured to the exposed face of the insole blank 1 in accordance with any appropriate procedure. As illustrated in the patent to Poole, 1,244,891, the sewing rib consists of a strip of cloth which is folded upon itself longitudinally to form the rib, with its margins laid in contact with the insole blank and secured thereto, either by adhesive or stitches. In accordance with the present invention, stitches may not be employed because of the presence of the reinforce member 2 during the rib-attaching operation, and thus it is necessary to employ adhesive in securing the margins of the rib-forming strip to the blank 1. In the patent to Poole, 1,137,282, the ribbing comprises a stiff core member in addition to the longitudinally folded textile strip, and in accordance with the present invention, the rib may be made either with or without such a core.

Referring to Fig. 7, there is diagrammatically indicated a conventional folder device 4, comprising a guide member 5, which receives the cloth strip 6 which is to form the outer element of the sewing rib, the guide being so devised as progressively to fold the strip as the assem-

bled blank 1 and reinforce 2 are moved in the direction of the arrow—the strip 6 being progressively folded and advanced by such mechanism as is well known in the art, while at the same time, if desired, a core member 7 (Fig. 12) is introduced between the folds of the strip 6. Adhesive is introduced between the strip and blank before the strip is brought into contact with the blank 1, and the margins of the strip 6 are pressed against the blank 1 and held in contact with the blank until the adhesive has set. After the rib has thus been applied to the blank 1 so as to follow the contour of the blank, as illustrated in Fig. 8, any other desired operations may be performed, for example, the trimming off of surplus rib material at the rear end portion of the sole blank; the application of a customary ply of textile fabric to that area of the blank which is bounded by the rib; etc. After the completion of any such operations, the reinforce member 2 is removed, leaving a complete insole as illustrated in Figs. 10, 11 and 12, wherein the thin flexible member 1 has the attached sewing rib 8 on one face.

While fiberboard has been suggested as useful in preparing the reinforce element, other materials may be employed. For example, sheet metal may be used, and because of its greater stiffness, it may be thinner and lighter in weight than the fiberboard. Such a metal stiffener might be provided with mechanical fastening means for temporarily holding it in assembled relation with the blank. Moreover, other means of temporarily stiffening the blank, for instance, by the use of removable coating or impregnants, are within the purview of the invention.

The present procedure has the very substantial advantage that by the use of the temporary reinforcing means, it becomes possible to apply a sewing rib to much thinner and more pliable insole stock than has heretofore been possible, so that the resultant insole may be of any desired degree of longitudinal flexibility, although smooth and flat and devoid of wrinkles.

While one desirable embodiment of the invention has herein been disclosed by way of example, it is to be understood that the invention is broadly inclusive of any and all modifications falling within the scope of the appended claims.

I claim:

1. That method of preparing Goodyear welt insoles, which comprises as steps providing an insole blank of thin, flexible material, providing a reinforce member of stiff sheet material having plane parallel upper and lower surfaces, said reinforce member being free and independent of other parts and being of approximately the same size and contour as the insole blank, whereby the reinforce member and blank may be assembled with their marginal edges in registry, the reinforce member being so light in weight that when assembled with the insole blank, the assembly may be handled and manipulated in the same way as a conventional insole blank of substantial thickness and inherent stiffness, placing the insole blank and reinforce member in registry with one another and temporarily uniting them, providing a narrow strip of rib-forming material wholly independent of the blank, so uniting said strip to the marginal portion only of the exposed surface of the insole blank as to form a sewing rib while leaving the surface of the blank exposed in the space bounded by the rib, and thereafter separating the reinforce member from the insole.
2. The method of preparing Goodyear welt

insoles, which comprises as steps providing a reinforce member of stiff sheet material of the size and contour of the insole which is to be made, providing an insole blank of thin, flexible material of a size and contour substantially like that of the reinforce member, placing the blank and reinforce member in registry and temporarily uniting them by means of adhesive, folding a flat strip of flexible material, initially separate from and independent of the insole blank, to form a sewing rib while progressively uniting the strip to the exposed surface of the insole blank, and thereafter removing the reinforce member from the blank.

3. That method of preparing Goodyear welt insoles, which comprises as steps providing a reinforce member of stiff sheet material having flat, parallel, opposite faces and which is of the size and contour of the insole which is to be made, providing an insole blank of thin, flexible material of a size and contour substantially like that of the reinforce member, placing the blank and reinforce member in registry and temporarily uniting them by means of adhesive binders, progressively laying a core strip in contact with the exposed surface of the insole blank while concomitantly folding a covering strip, initially separate from and independent of the blank, about the core and uniting the margins of the covering strip to the insole blank, thereby to form a sewing rib, and thereafter removing the reinforce member from the blank.

4. That method of preparing Goodyear welt insoles which comprises as steps, forming a structure, capable of being handled as a unit, by applying to one face of a thin, normally very pliable insole blank, temporary stiffening means, not substantially exceeding two irons in thickness, progressively securing to the other face of the blank, while the latter is stiffened by association with said stiffening means, a sewing rib which is initially separate from and independent from the blank, and, after the rib is complete, removing said stiffening means to restore the blank to its initial pliability.

5. That method of making an insole having a sewing rib which comprises as steps, providing an insole blank of thin, flexible material, temporarily applying to one face of said blank a thin layer of stiffening material of substantially uniform thickness and whose edge registers with that of the blank, attaching, to the opposite face of said blank, rib-forming material which is initially separate from and independent of the blank, beginning at a selected point near one edge of the blank and causing the point of attachment to progress, following the contour of the blank, until the rib is completed, and, after

so attaching the rib-forming material, removing the layer of stiffening material.

5 6. That method of making an insole having a sewing rib which comprises as steps providing an insole blank of thin, flexible material of uniform thickness, temporarily attaching to one face of the blank a stiffener element, attaching to the other face of the blank rib-forming material, beginning at a selected point near one edge of the blank and causing the point of attachment to progress, following the contour of the blank until the rib is completed, and after the rib is complete removing the stiffener element.

15 7. That method of making a Goodyear-type insole which comprises as steps providing a single-ply insole blank of thin, flexible material, providing a stiffener element of sheet material and of a size and contour like that of the blank, placing the blank and stiffener element in registry with one face of the blank in contact with the stiffener element, temporarily uniting the blank and stiffener element, attaching, to the exposed face of the blank, rib-forming material which is initially separate from and independent 20 of the blank, beginning at a selected point near one edge of the blank and causing the point of attachment to progress following the contour of the blank until the rib is complete, and after completion of the rib separating the stiffener element from the insole.

25 8. That method of making a Goodyear-type insole which comprises as steps, forming a freely movable unit, of a weight not substantially exceeding that of a conventional Goodyear insole and which is capable of being handled like such a conventional Goodyear insole, by temporarily stiffening a thin, normally very pliable insole blank by means which does not increase the thickness of said blank by substantially more 30 than two irons, attaching to the blank, rib-forming material which is initially separate from and independent of the blank, beginning at a selected point near one edge of the blank and causing the point of attachment to progress following the contour of the blank until the rib is complete, and after completion of the rib, restoring the blank substantially to its initial pliability.
